(57) **CLAIM**

The ornamental design for a handle for a hair styling apparatus as shown and described.

DESCRIPTION

The patent or application file contains at least one drawing executed in color. Copies of this patent or patent application publication with color drawing(s) will be provided by the Office upon request and payment of the necessary fee.

1. Handle for a hair styling apparatus

Fig. 1.1 is a perspective view of the handle for a hair styling apparatus showing my new design;

Fig. 1.2 is a bottom view thereof;

Fig. 1.3 is another perspective view thereof;

Fig. 1.4 is an enlarged front view thereof;

Fig. 1.5 is an enlarged rear view thereof;

Fig. 1.6 is a top view thereof;

Fig. 1.7 is a left side view thereof; and

Fig. 1.8 is a right side view thereof.

The portions of the design shown in the color red illustrate elements that form no part of the claimed design.
